UNITED STATES PATENT OFFICE.

CLAUS VAN HAAGEN, OF PHILADELPHIA, PENNSYLVANIA.

MANUFACTURE OF DRILLS.

SPECIFICATION forming part of Letters Patent No. 296,254, dated April 1, 1884.

Application filed August 6, 1883. (No model.)

To all whom it may concern:

Be it known that I, CLAUS VAN HAAGEN, a citizen of the United States, and a resident of Philadelphia, Pennsylvania, have invented 5 certain Improvements in the Manufacture of Drills, of which the following is a specification.

The object of my invention is to rapidly and economically produce by forging drills such as are known as "twist-drills;" and this object I attain in the manner hereinafter set forth, reference being had to the accompanying drawings, in which—

Figures 1, 2, 3, 4, and 5, Sheet 1, are diagrams illustrating the method of forging twist-drills in accordance with my invention; Fig. 6, Sheet 2, a side elevation of a machine for making drills in accordance with my invention; Fig. 7, Sheet 1, a sectional plan of part of Fig. 6 on the line 1 2; Fig. 8, Sheet 3, a face 20 view of the machine with the cap-plate removed and part shown in section; Fig. 9, Sheet 25 6, a sectional plan, on an enlarged scale, on the line 7 8, Fig. 6; Fig. 12, Sheet 7, a plan view of the machine on a reduced scale; and Figs. 13, 14, 15, and 16, detached views of parts of the machine.

An understanding of the process forming part of my invention may be had on reference to Figs. 1 to 5, which illustrate the manner of forging the drill. A rod, A, is first prepared, and this rod, properly heated, is introduced between 30 a pair of clamping-dies, B B', in which are recesses d , forming openings for the passage of the opposite hammers D D'. The dies being closed upon the rod, so as to firmly retain the same, the hammers are thrust through 35 the openings and caused to indent the opposite sides of the rod, as shown in Fig. 3, the ends of the hammers being rounded to accord with the desired shape of the grooves in the drill, and the said hammers being inclined in 40 accordance with the pitch of the spiral groove of the drill. After acting upon the rod, the hammers are retracted and the dies B B' opened, as shown in Fig. 4, thus releasing the rod, which is now moved forward to a limited 45 extent, and at the same time slightly turned, the dies then closing and the hammers acting as before. By repeating these operations op-

posite spiral grooves will be formed in the rod, as shown in Fig. 5, the pitch of the grooves depending upon the inclination of the hammers and the feed of the rod and their depth upon the extent of the inward thrust of the hammers. This inward thrust is controlled so that at the commencement of the operation the rod A will be but slightly indented, the thrust 55 being gradually increased as the rod is moved backward and forward through the clamping-dies until a groove of the proper depth is formed. The rod A is preferably of hexagonal, octagonal, or oval cross-section, so that while 60 the dies can clamp the same vertically the rod will not fill the opening in the dies, but will be free to expand as it is indented by the hammers. It is not absolutely essential that the rod should have a definite turning as well as a 65 longitudinal movement imparted to it, as the turning movement may be effected by the action of the inclined hammers after the formation of the groove has been started. It is preferable, however, to impart a spiral feed to the 70 drill-rod in order to insure accuracy in the formation of the groove.

The organized machine for making drills in accordance with my invention is shown in Figs. 6 to 16, in which D D' represent the 80 hammers carried by slides a a' , operated by eccentrics a^2 a^2 on the driving-shaft F, and adapted to suitable guides in the frame G of the machine, the slide a' being forked, as shown in Figs. 8 and 9, so as to provide an 85 opening for the clamping-dies B B', and the slide a being arranged at one side of the slide a' , but having a portion projecting into the central recess of the latter, so that the two 90 hammers operate in line with each other, as shown in Fig. 7. The throw of the slides and hammers is uniform, being determined by the eccentrics a^2 ; but in order to vary the extent to which the hammers are caused to indent the drill-rod, I make said hammers adjustable 95 in respect to the slides by means shown in Figs. 7, 8, and 11. The stem of each hammer is threaded and adapted to a nut, b, confined longitudinally to, but free to turn in, the hammer-slide, and having a worm-wheel, e, to 100 which is adapted a worm, e' , on a shaft carried by the slide, and having a bevel-wheel, e^2 . These bevel-wheels e^2 gear into bevel-pinions f , which are confined to brackets f' on the

slides, Fig. 8, and are adapted to a shaft, g , which is longitudinally confined to a bearing, g' , Fig. 11, on the frame, but is free to be rotated by means of bevel-gearing $g^2 g^3$ and a shaft, g' , the latter being adapted to bearings in a projection, g' , of the frame, and being furnished with a suitable hand-wheel. The pinions f are free to move to and fro on the shaft g as the slides $a a'$ are reciprocated; but to each pinion has a spline adapted to a groove in the shaft, so that it must rotate therewith; hence by turning the shaft in one direction or the other the nuts b will be turned and the hammers $D D'$ advanced or retracted.

15 The lower clamping-die, B' , is stationary, being confined to a block, h , on the frame; but the upper die, B , is carried by a sliding box, H , guided in a vertical projection, H' , of the frame, and acted upon by a spring, i , which is confined between the upper end of the box and the head i' of a pendent bolt, i^2 , the effect of the spring thus being to elevate the box and the die carried thereby. The box is recessed for the passage of the upper arm of the slide a' , and on said arm is a wedge-block, m , adapted to bear upon a corresponding wedge-block, n , carried by the box H , the wedges being partly inclined and partly straight, as shown in Fig. 8, so that as the slide is moved 20 to thrust the hammer D' inward the wedges will engage with each other and the clamping-die B will be depressed and locked in that position, so as to clamp the drill-rod before the hammers commence to act upon the same, 25 the spring causing the elevation of the die as the wedge-block m is drawn back on the reverse movement of the hammer-slide a' .

30 The drill-rod is clamped in a chuck, J , on a carriage, K , which is guided by and is free to slide on a tubular projection, M , of the frame, this movement being effected by a rack, k , and pinion k' , as shown in Figs. 9, 13, and 14. This movement is simply for the purpose of adjusting the drill-rod to the clamping-dies 35 in the first instance, and for retracting the same after the forging operation is completed. The stem of the carriage has a movement independent of the carriage, this movement being that relied upon for feeding the drill-rod spirally during the forging operation.

40 The chuck consists simply of a pair of jaws operated by a right and left handed screw-stem, p , as shown in Figs. 9 and 15; or any other desired form of clamping-chuck may be used. The stem of the chuck is threaded 45 and adapted to a nut, q , which can turn in but is confined longitudinally to the carriage, and said stem has a spline adapted to a groove in a shaft, P , secured to which is a worm-wheel, s , driven by a worm, t , Fig. 13, 50 on a shaft, t' , the latter being driven by bevel-gearing $t^2 t^3$ from a shaft, w , and said shaft by spur-gearing $w' w^2$ from a shaft, W , which is furnished with a suitable hand-wheel, W' , 55 Figs. 6 and 12, and carries a spur-wheel, W^2 , Fig. 9, gearing into a pinion, x , on the nut q . It will thus be seen that as the shaft W is

60 turned the nut q will be rotated, so as to feed the stem of the chuck forward or backward, while at the same time the chuck will be rotated by means of the spur-and-worm gearing and shaft P , the amount of feed of the chuck being due to the number of turns imparted to the nut q by its gearing in excess of those imparted to the stem by the shaft P .

65 If desired, but one hammer may be used for indenting the drill-rod, and but one groove at a time may be formed in the same; but the use of two hammers is of course preferred.

70 My invention is distinct from the plan which has been proposed of forging twist-drills with two sets of dies, to the action of which the drill-rod is alternately exposed, one set of dies having oblique ribs for forming the grooves in the rod, and the other set being swaging or 75 reducing dies.

75 The main feature of my invention is in confining the drill-rod while the hammers act upon it so that lateral spreading is prevented, and subsequent reduction of the rod rendered 80 unnecessary.

85 I claim as my invention—

1. The mode herein described of forging drills, said mode consisting in feeding the drill-rod longitudinally and subjecting the 90 same to the action of a reciprocating hammer or hammers while it is confined, so as to prevent lateral spreading, as set forth.

2. The mode described of forging drills, said mode consisting in simultaneously turning and 95 longitudinally feeding the drill-rod and subjecting the same to the action of a reciprocating hammer or hammers while it is confined, so as to prevent lateral spreading, as set forth.

3. The combination of a pair of clamping- 100 dies, mechanism for feeding a drill-rod longitudinally through the same, a hammer arranged at an angle to the longitudinal axis of the drill-rod, and mechanism for reciprocating the hammer, as set forth.

4. The combination of the clamping-dies B B' , the hammers $D D'$, and a drill-rod-holding chuck, with mechanism, substantially as described, for operating the dies, reciprocating the hammers, and spirally feeding the chuck, 105 as set forth.

5. The combination of the hammer or hammers, the clamping-dies B B' , having recesses d for the reception thereof, and mechanism, 110 substantially as described, for reciprocating said hammer or hammers, opening and closing the dies, and feeding a drill-rod longitudinally through the same, as set forth.

6. The combination of the upper clamping-die, B , and its wedge-block n , partly inclined 115 and partly straight, the hammer-slide a' and its wedge-block m , adapted to the block n , and a spring, i , adapted to elevate the die B and maintain the wedge-blocks in contact with each other, as set forth.

7. The combination of the hammer-slide, the hammer adjustable therein, and having a threaded stem, nut adapted to said stem, a longitudinal shaft, g , and mechanism, substan- 120

tially as described, whereby said shaft *g* is geared to the nut, as set forth.

8. The combination of the carriage K, threaded chuck-stem, nut *g*, shaft P, and mechanism for rotating said shaft and nut, as set forth.

In testimony whereof I have signed my name

to this specification in the presence of two subscribing witnesses.

CLAUS VAN HAAGEN.
